UNITED STATES PATENT OFFICE.

JOSEPH B. SCHAEFER, OF CELINA, OHIO.

BABY-CARRIAGE.

1,256,379.

Specification of Letters Patent. Patented Feb. 12, 1918.

Application filed March 30, 1917. Serial No. 158,719.

To all whom it may concern:

Be it known that I, JOSEPH B. SCHAEFER, a citizen of the United States, residing at Celina, in the county of Mercer and State 5 of Ohio, have invented certain useful Improvements in Baby-Carriages, of which the following is a specification, reference being had therein to the accompanying drawing.

10 The invention relates to baby carriages, and more particularly to the class of convertible baby carriage bodies.

15 The primary object of the invention is the provision of a carriage body of this character wherein either twins or two babies of different ages can be easily placed and conveniently held therein without discomfort to either one or both and the operator of the carriage.

20 Another object of the invention is the provision of a carriage body of this character wherein the construction thereof permits its use for two occupants, either both in sitting attitude, one reclining and the 25 other seated, or for a single occupant either seated or reclining, thereby making the body convertible for the convenience of the occupants or users.

20 A further object of the invention is the provision of a carriage body of this character wherein the construction thereof is novel in form so that when holding two occupants the same can face each other or both occupants face in the same direction and each 35 occupant will be assured of comfort and without possibility of disturbing the other occupant.

30 A still further object of the invention is the provision of a carriage body of this 40 character which can be readily and easily converted for a single or two occupants and is simple in construction, thoroughly reliable and efficient in its purpose, strong, durable and inexpensive in manufacture.

45 Other objects will be in part obvious and in part hereinafter set forth.

50 The invention accordingly consists in the features of construction, combination of elements and arrangement of parts which will be exemplified in the construction herein- 55 after described, and the scope of the application of which will be indicated in the appended claims.

In the accompanying drawings:

55 Figure 1 is a perspective view of a baby

carriage with the body constructed in accordance with the invention;

Fig. 2 is a side elevation with the side panel broken away;

Fig. 3 is a rear elevation;

60

Fig. 4 is a top plan view;

Fig. 5 is a vertical longitudinal sectional view;

Fig. 6 is a vertical transverse sectional view on the line 6—6 of Fig. 2.

65

Similar reference characters indicate corresponding parts throughout the several views of the drawings.

Referring to the drawings in detail, the baby carriage body A comprises side frames 70 10 which support intermediate channel guide rails 11 on which are fixed front and rear seat sections 12 and 13, respectively, which are spaced apart to provide a leg or foot opening 14, while supported by the side 75 frames 10 below the plane of the seat sections 12 and 13 is a floor section 15 which constitutes a foot rest, and at the front and rear edges of this floor section are vertical partitions 16 which are fastened to the side 80 frames 10 so as to constitute an inclosure for the legs and feet of the occupants of the carriage body when the same are in sitting position upon the seat sections 12 and facing each other.

85

The side frames 10 have fixed thereon panels 17 which are correspondingly shaped thereto and constitute the closed sides of the carriage body.

Mounted within the channels of the guide 90 rails 11 are front and rear slides 18 and 19, respectively, which are adapted to alternately close the leg opening 14 between the seat sections 12 and 13, the front slide 18 being manually moved, and the same is provided with a finger hole 20, while the rear slide 19 is automatically moved in a manner presently described.

95

At the front end of the carriage body is a front seat back 21 which is supported upon 100 arms 22 pivoted to hanger strips 23 mounted in the side frames 10 so that the front seat back 21 can be swung to assume two positions, whereby the occupant of the seat can face the front of the carriage body or face 105 the rear thereof, as will be obvious, the seat back 21 when in either position being designed to rest upon the front seat section 12, as will be apparent.

Located at the rear end of the carriage 110

body is a rear seat back 24 which is mounted on swinging side levers 25 supported on pivots 26 carried by the side frames 10. To the lower ends of these levers are pivoted links 5 27 which are also pivoted to a bracket 28 fixed to the under side of the rear slide 19 so that on swinging the rear seat back 24 the said slide 19 will be moved simultaneously therewith.

10 Pivoted to one of the sides frames 10 is a latch arm 29 to which is pivotally connected the lower end 30 of an operating stem or rod 31 slidably mounted in the side frame 10, and this latch arm 29 is formed with a plurality of notches 32 to receive a keeper pin 33 mounted in one of the links 27, and when the pin engages in any one of the notches 32 the rear seat back 24 is held in its adjusted position and likewise the rear slide 19 is 15 locked against movement. Surrounding the stem or rod 31 is a coiled expansion spring 34, the lower end of which works against a washer 35 fixed on the rod or stem 31 against displacement, while the opposite end of said 20 spring 34 works against a washer 36 abutting the top rail of the side frame 10, and this spring 34 is designed to normally hold the latch arm 29 in position for locking engagement with the keeper pin 33 and there- 25 by securing the rear seat back 24 and rear slide 19 against movement. The upper end of the rod or stem 31 carries a finger ring 37 which permits the convenient manipulation of the rod or stem to move the same against 30 the resistance of the spring 34 when it is desired to release the rear seat back and the 35 rear slide, as will be obvious.

Arranged at the front end of the carriage body below the front seat section 12 is a 40 swinging foot rest section 38 pivoted in bearings 39 carried by the side frames 10, and this section 38 carries a spring-pressed latch 40 for engagement in a keeper 41 mounted in the under face of the front seat section to 45 hold the said foot rest or section 38 in its normal vertical position, while on the outer side of the section or rest 38 is a swinging handle 42 which permits the lowering of the foot rest or section 38 for use. Pivoted to 50 one side of the foot rest or section 38 is a brace 43 which is slidably engaged with a guide pin 44 mounted on one of the side frames 10, and this brace supports the foot rest or section 38 in its lowered horizontal 55 position, as will be obvious.

When the carriage body is used for occupancy by twins or two babies or children the slides 18 and 19 are normally located below the seat sections 12 and 13 so that the said 60 seat sections can be occupied when the babies or children are in sitting attitude and the same can face each other or face in a forward direction, and the latter instance is effected by the shifting of the front seat back 65 and the lowering of the foot rest or section

38, the front seat back being positioned at the rear of the front seat section. Now on moving either slide 18 or 19 over the opening 14 the carriage body will be converted for use as a bed for the infants or children and 70 either one or two children can occupy the same. If desired, the rear seat back can be lowered to the desired degree so that one infant can recline or rest in lying position while another infant can be seated on the 75 front seat section 12 without inconvenience to either or both of the occupants.

From the foregoing description, taken in connection with the accompanying drawings, the construction and manner of use of the 80 herein described baby carriage will be readily apparent and, therefore, a more extended explanation has been omitted.

Having thus described my invention, I claim:

1. A carriage body of the character described comprising side frames, front and rear seat sections between the side frames and supported thereby in spaced relation to each other, front and rear slides movable beneath the seat sections, a front seat back 85 swingingly supported between the side frames at the front ends thereof and co-acting with the front seat section, a rear seat back adjustably supported between the 90 side frames at the rear ends thereof and having connection with one of the slides for moving the same with said rear seat back, and a floor section supported by the side frames below the space between the seat sec- 95 tions. 100

2. A carriage body of the character described comprising side frames, front and rear seat sections between the side frames and supported thereby in spaced relation to 105 each other, front and rear slides movable beneath the seat sections, a front seat back swingingly supported between the side frames at the front ends thereof and co-acting with the front seat section, a rear seat back adjustably supported between the 110 side frames at the rear ends thereof and having connection with one of the slides for moving the same with said rear seat back, a floor section supported by the side frames 115 below the space between the seat sections, and means for locking the rear seat back in adjusted position.

3. A carriage body of the character described comprising side frames, front and 120 rear seat sections between the side frames and supported thereby in spaced relation to each other, front and rear slides movable beneath the seat sections, a front seat back swingingly supported between the side 125 frames at the front ends thereof and co-acting with the front seat section, a rear seat back adjustably supported between the side frames at the rear ends thereof and having connection with one of the slides for 130

moving the same with said rear seat back, a floor section supported by the side frames below the space between the seat sections, means for locking the rear seat back in adjusted position, and a swinging foot rest supported at the front ends of the side frames below the front seat.

4. In a carriage body, a pair of seats spaced from each other to form a leg opening therebetween, a floor section below the seat sections at the point of location of the leg opening therebetween, partitions forming an inclosure for the space between the seat sections and the floor section, movable backs for the respective seats, manually and automatically movable slides located beneath the seat sections for closing the leg opening therebetween, and connections between one of the seat backs and said automatically movable slide for actuating the same.

5. In a carriage body, a pair of seats spaced from each other to form a leg opening therebetween, a floor section below the seat sections at the point of location of the leg opening therebetween, partitions forming an inclosure for the space between the seat sections and the floor section, movable backs for the respective seats, manually and

automatically movable slides located beneath the seat sections for closing the leg opening therebetween, connections between one of the seat backs and said automatically movable slide for actuating the same, and means for co-action with the connections to hold the seat back and automatically movable slide in adjusted position.

6. In a carriage body, a pair of seats spaced from each other to form a leg opening therebetween, a floor section below the seat sections at the point of location of the leg opening therebetween, partitions forming an inclosure for the space between the seat sections and the floor section, movable backs for the respective seats, manually and automatically movable slides located beneath the seat sections for closing the leg opening therebetween, connections between one of the seat backs and said automatically movable slide for actuating the same, means for co-action with the connections to hold the seat back and automatically movable slide in adjusted position, and a drop foot rest located beneath the seat section at the front end of the body.

In testimony whereof I affix my signature.

JOSEPH B. SCHAEFER.
